UNITED STATES PATENT OFFICE.

FORREST C. PARKS, OF PITTSBURGH, PENNSYLVANIA, ASSIGNOR OF ONE-HALF TO
CHARLES C. GRAHAM, OF CHICAGO, ILLINOIS.

STERILIZING APPARATUS.

1,237,375.

Specification of Letters Patent. Patented Aug. 21, 1917.

Application filed October 23, 1916. Serial No. 127,181.

To all whom it may concern:

Be it known that I, FORREST C. PARKS, a citizen of the United States, residing at Pittsburgh, in the county of Allegheny and State of Pennsylvania, have invented certain new and useful Improvements in Sterilizing Apparatus, of which the following is a specification.

This invention relates broadly to improvements in sterilizing apparatus, and refers particularly to an apparatus for sterilizing glasses, dishes or any other analogous objects.

One object of this invention is to provide a sterilizing apparatus of the type set forth that will subject every part of the dish or object to the action of the sterilizing agent, and which in addition to sterilizing the object will thoroughly dry it.

Another object of this invention is to provide a sterilizer of the character described which will have a large capacity and thus be able to sterilize a great many objects and which will require very little attention, making its operating cost very small.

Further objects of this invention are the provision of a sterilizing apparatus which may be heated by electricity, steam, gas or any other source of heat, and whereby access may be had to one of the drawers independent of the remaining drawers and the sterilizing chamber remaining in a closed position while placing dishes or objects in said drawers or while removing same therefrom.

Still further objects of this invention are to provide a device of the character set forth, which is simple in its construction and arrangement, strong, durable and efficient in its use and inexpensive to manufacture.

To the accomplishment of these and such other objects as may hereinafter appear, the invention consists of the novel construction, combination and arrangement of parts herein specifically described, and illustrated in the accompanying drawings, wherein is shown an embodiment of the invention.

In the drawings, forming a portion of

this specification and wherein like numerals 50 of reference designate corresponding parts throughout the several views:

Figure 1 represents a perspective view of the sterilizing apparatus in accordance with this invention.

55

Fig. 2 is a perspective view of the drawers embodied in this invention.

Fig. 3 is a vertical cross sectional view of the drawer and the side walls of the body of the sterilizer, said side walls being 60 broken away.

Fig. 4 is a fragmentary perspective view of the sterilizer showing the latching device for holding the drawers in closed position.

Fig. 5 is a plan view of the bottom of the 65 sterilizing chamber, having an electric heating unit mounted thereon.

Referring more in detail to the drawings, 1 represents the body of the sterilizer, preferably rectangular in shape and constructed of sheet metal. The body 1 consists of the outer casing 2 and the inner lining 3, having interposed therebetween the filler 4 of asbestos or any other suitable non-conductor of heat.

75

The body 1 is provided with the door 5 opening into the sterilizing chamber 6 to afford access into the said chamber and to facilitate the cleaning thereof, or for making any repairs therein or to associated 80 parts.

The body 1 is further provided with the openings 7 in the side walls 8 and 9 respectively. The openings 7, on the side wall 8 and those in the side wall 9, are positioned 85 parallel to each other, for the reception of the drawers 10, which extend transversely through the said openings 7 and through the sterilizing chamber 6.

As illustrated in Fig. 2, the drawers 10 90 are constructed to form the two sections 11 and 12, which are divided by the partition 13. Each of the drawer sections 11 and 12 is provided with an end portion 14, and is of sufficient length to extend entirely 95 through the body 1 in openings 7 in the side walls 8 and 9. It will thus be obvious that when one of the sections of the drawer is in

the closed position the other section of the said drawer will necessarily be in the open or extended position.

By referring more particularly to Fig. 3 of the drawings it will be seen that while section 11 of the drawer 10, is in the closed position and extending through the sterilizing chamber 6, the end portion 14 of the said section and the partition 13 will completely close the openings 7 in the side walls 8 and 9, thereby retaining the heat or sterilizing agent within the said chamber. While the objects in the drawer section 11 are being subjected to the sterilizing agent, the sterilized objects in the drawer section 12, which is in the open or extended position, may be removed therefrom, and other objects to be sterilized placed therein.

The end portions 14 and the partition 13 of the drawers 10 are made preferably of the same material as the body 1, and are provided with a filler 15 of the same material as is interposed between the outer casing 2 and the inner lining 3 of the body 1, to aid in the retention of the sterilizing agent (heat) within the sterilizing chamber 6.

The sides 16, the ends 17 and the bottoms 18 of the drawer sections 11 and 12 are attached to the end portions 14 and to the partition 13 by means of the bolts or screws 19 in such a manner that the said drawer may be taken apart when it is desired to remove the same from the openings 7 in the body 1, for making repairs, etc.

In a sterilizer of the type embodied in this invention, the only time that the sterilizing agent (heat) can escape from the sterilizing chamber 6, is during the operation of opening and closing one of the drawers 10, and as the said operation should be as easy and rapid as possible, the said drawers may be provided with roller bearings (not shown) or their equivalent, if the sterilizer is of a large size and heavily constructed.

To allow the sterilizing agent to more thoroughly permeate the sterilizing chamber 6 and the objects contained therein, the sides 16 and the bottoms 18 of the drawer sections 11 and 12 are provided with perforations 20, of a suitable number and size. If desired the bottoms 18, may be constructed from wire netting.

The drawers 10 are provided with suitable pulls 22, and with the latching devices 23 for holding the said drawers securely in the closed position.

A thermometer 24, adapted to indicate the temperature of the sterilizing chamber 6, is positioned in the door 5, which is also provided with the latch device 25.

The stepped contour 26 of the peripheries

of the openings 7 in the walls 8 and 9 of the body 1, and in the door opening 27, are provided to engage the corresponding stepped contour 28 of the peripheries of the door 5, of the end portions 14 and of the partitions 13, of the drawers 10, for the purpose of more closely confining the heat in the sterilizing chamber 6.

As the sterilizing agent, used in connection with this sterilizer, is heat, the same may be generated by any means desirable, and while illustrating in Fig. 5, of the drawings, a heating device 29, consisting of an ordinary electric heating unit mounted upon the floor 30 of the sterilizing chamber 6, for the purpose of generating the heat, gas, steam, oil, etc., with appropriate fixtures and attachments, can readily be substituted.

From the foregoing description, taken in connection with the accompanying drawings, the advantages of the construction and the method of operation will be readily apparent to those skilled in the art to which this invention appertains, and while describing the principle of operation of the invention together with the device which is now considered to be the best embodiment thereof, it is to be understood that the device is merely illustrative as shown and that various changes in the form, proportion and the minor details of construction may be resorted to without departing from the principle or sacrificing any of the advantages of the invention as defined in the appended claims.

What I claim as new and desire to secure by Letters Patent is:

1. In a sterilizing apparatus comprising a body portion forming a sterilizing chamber, and a plurality of drawers each consisting of two sections extending transversely through the said body portion and so arranged that when a section of the said drawers is in the closed position the other section thereof is in the open or extended position.

2. A sterilizing apparatus comprising a body portion, consisting of an outer casing, an inner lining and a filler of non-heat-conducting material interposed between the said outer casing and the said inner lining, a drawer, having two compartments and slidably mounted, extending transversely through oppositely disposed openings in the walls of the said body portion, the combined length of the said two compartments being twice that of the body portion, so that one of the said compartments is arranged exteriorly of the said body portion, and certain walls of the body portion having an interfitting connection with certain walls of the drawer, substantially as described and set forth.

3. A sterilizing apparatus comprising a body portion, consisting of an outer casing, an inner lining and a filler of non-heat-conducting material interposed between the said outer casing and the said inner lining, a drawer, having two compartments, extending transversely through, and slidably mounted in oppositely disposed openings in the walls of the said body portion, a sterilizing chamber, a door having a suitable latching device opening into the said sterilizing chamber, means for removing the said
- 5
- 10

drawer from said oppositely disposed openings, and certain walls of the body portion having an interfitting connection with certain walls of the said drawer, substantially as described and for the purpose set forth. 15

In testimony whereof I affix my signature in the presence of two witnesses.

FORREST C. PARKS.
